UNITED STATES PATENT OFFICE.

LESTER PERRINE, OF DETROIT, MICHIGAN.

COMPENSATING JAW FOR CHUCKS AND THE LIKE.

Application filed March 18, 1921. Serial No. 453,267.

To all whom it may concern:

Be it known that I, LESTER PERRINE, a citizen of the United States, residing at Detroit, in the county of Wayne and State of Michigan, have invented certain new and useful improvements in a Compensating Jaw for Chucks and the like; and I do hereby declare the following to be a full, clear, and exact description of the invention, such as will enable others skilled in the art to which it appertains to make and use the same.

The object of the invention is to provide an automatically compensating jaw for use in connection with shaper and milling machines, vises, lathe chucks, jigs, etc., wherever there is a possibility of encountering an irregularity in shape of the article to be grasped or clamped, so that jaws of fixed and conventional forms, operating on straight lines or having parallel faces are not adapted to obtain a firm hold and maintain the object against movement or vibration while the machine is in operation or while the object so engaged or grasped is being operated upon; and more specifically to provide a jaw which adapts itself to any irregularities in the surfaces of the object which is to be gripped while maintaining a sufficiently firm pressure upon the surfaces thereof by the several gripping elements, to insure the proper positioning of the object; and with these objects in view the invention consists in a construction and combination of parts of which a preferred embodiment is shown in the drawing, wherein

Figure 1 is a view of a gripper jaw of conventional form provided with the compensating object-engaging element constructed in accordance with the invention;

Fig. 2 is a sectional view of the same taken longitudinally; and

Fig. 3 is an end view.

The jaw 10 may be of any preferred form or dimensions suited to the machine in connection with which the same is to be used and in the operation of which it is necessary to grip or engage an object to hold it in proper position to be shaped or milled or turned or otherwise operated upon, said jaw being provided with compensating gripping elements 11 consisting of pins which are slidingly fitted in guides 12 in the face of the jaw in terminal contact with oppositely cupped followers 13 of lead or brass, said guides 12 being in communication with an equalizing passage 14 provided with a filler

of oil, grease, wax, rubber or any equivalent thereof having a yielding characteristic and adapted when one of the elements is repressed to convey pressure through the communicating passage 14 to the guides in which the other elements of the gripper are mounted with a consequent tendency to advance said other elements. The tendency of the followers, by reason of their cupped form is to spread so as to prevent the leakage of the filler and maintain it in the inner ends of the guides 12 and the communicating or equalizing passage 14, one end of the latter being accessible by means of a removable plug 15 so that the filler may be introduced. When the jaw is brought into forcible contact with an object to be gripped, therefore, any projecting portion of the surface of the object, should it be of irregular form, will as above indicated tend to repress one or more of the elements 11 and in so doing by reason of the compensating relation of the elements, the other units thereof will be forced outward into engagement with adjacent depressed portions of the objects, and when all of the elements have been brought into firm engagement with the object, they will bear with equal force and gripping action upon the several portions of the surface of the objects and therefore will serve to firmly hold the latter during the operation of the machine.

Having thus described the invention, what I claim is:

1. A gripper jaw having independently movable gripper elements to directly contact with the surface gripped and fitted in communicating guides provided with a mobile filler and capable of substantial movement in said guides whereby the elements will automatically adapt themselves to the contour of the said surface.

2. A gripper jaw having independently movable gripper pins movable in directions at an angle to the face of the jaw to directly contact with the surface gripped and fitted in communicating guides provided with a mobile and substantially incompressible filler the pins extending a substantial distance beyond said face and being unobstructed beyond the same for a distance to permit substantial movement thereof, whereby the elements will automatically adapt themselves to the contour of the said surface.

3. A gripper jaw having guides disposed

at an angle to the face thereof and connected by an equalizing passage, gripper elements fitted respectively in said guides to directly contact with the surface gripped, a sluggish 5 filler occupying said passage and the communicating ends of the guides whereby the elements will automatically adapt themselves to the contour of the said surface, following elements being disposed in the guides 10 for the terminal contact of said gripper elements one element in each guide being

cupped and the coacting element being shaped to snugly fit the cups to expand the same so as to function as a seal to prevent escape of the filler.

15

In testimony whereof I affix my signature in presence of two witnesses.

LESTER PERRINE.
